UNITED STATES PATENT OFFICE

GEORGE G. HARRINGTON, OF HOUSTON, TEXAS, ASSIGNOR TO REED ROLLER BIT COMPANY, OF HOUSTON, TEXAS, A CORPORATION OF TEXAS

DRILL

Application filed July 22, 1930. Serial No. 469,666.

This invention relates to deep well drilling apparatus and more particularly to that type of drill embodying removable cutting blades.

5 Cutting blades of deep well drills are quickly worn by most formations, and they are now removably mounted in the bit head of the drill so that they may be replaced. The blade mountings now in use are defective in that they permit movement of the blade in the bit head when the drill is subjected to the usually great drilling strains. 10 Becoming loose, the blades wear the head, cut a bore of a diameter other than that predetermined, and are often forced out of the head.

This invention has for its object the provision of a drill embodying removable cutting blades which cannot become loose during drilling operations.

The preferred embodiment of the invention for rotary core drills is illustrated by the accompanying drawings of which Fig. 1 is a side elevation of a drill bit head with blades removably mounted therein; Fig. 2, a sectional elevation at a right angle to Fig. 1; Fig. 3 a bottom plan view with the blades removed; and Fig. 4, a fragmentary sectional view taken on the line 4-4 of Fig. 3. 20 It will be understood that the invention may be embodied in various types of drills other than that herein shown.

In the drawings, the bit head 1 has therethrough a central, longitudinal bore 2 for the reception of the conventional core barrel, not shown. In the bottom of the bit head, on opposite sides of its axis, are twin blade slots, each of which opens outwardly and downwardly and has side walls 3 and 4 which converge upwardly and also converge transversely toward the periphery of the head; and an inner wall 5 extending substantially parallel with the longitudinal axis of the head. Each of the side walls 3 has a depending bearing extension 6, shown quite clearly by Fig. 4.

The upper portion of each of the blades 7 is tapered upwardly and also tapered outwardly and has a flat inner side, so that the 50 blades will fit snugly in the slots with their

rear sides resting against the bearing extensions 6. In each of the blades is a vertically elongated slot 8 for the reception of one of the retaining screws 9. The cutting portions of the blades may be of any desired form.

When it is desired to use the drill, the blades 7 are slipped into the slots and the screws 9 screwed into place. The screws 9 are not subjected to any appreciable strains, their function being merely to hold the blades 55 in the slots when the drill is being lowered or elevated in the hole.

Now when the blades are resting upon the bottom of the hole, and the great weight of the drill stem is placed upon them, they are 60 forced upwardly into a tight engagement with the walls of the slots. The screws 9 do not interfere with the upward movement of the blades because the slots 8 are vertically elongated. And when the drill is actuated in 65 drilling operations, the blades cannot become loose in the head because the weight of the stem continuously tends to force them tightly into the head, and the engaging walls of the blades and slots positively prevent lateral movement.

I claim:

1. A well-drilling bit blade having an upper portion both tapered toward its upper end and tapered toward its outer side, and 70 an elongated slot therein.

2. A rotary core drill bit head having therethrough a central longitudinal bore, downwardly and outwardly opening slots on opposite sides of its axis, the side walls of each of said slots converging upwardly and converging outwardly, one of the side walls of each of said slots having a depending bearing extension, the inner wall of each of said slots extending substantially parallel with the axis of the head, blades fitting snugly in said slots so that the rear side of each of said blades bears against one of said extensions, each of said blades having an axially elongated opening therein, and screws carried 85 by the head and extending through and fitting loosely in said openings.

3. A rotary drill bit head having downwardly and outwardly opening slots on opposite sides of its axis, the side walls of each of 90

said slots converging upwardly and converging outwardly, blades fitting snugly in said slots, each of said blades having an axially elongated opening therein, and screws carried by the head and extending through and fitting loosely in said openings, said blades being gripped by said walls when forced into said slots.

In testimony whereof, I hereunto affix my
10 signature.

GEORGE G. HARRINGTON.
